SHEET METAL BEAM

Albert G. Dean, Narberth, Pa., assignor to
 Edward G. Budd Manufacturing Company,
 Philadelphia, Pa., a corporation of Pennsylvania

Application March 28, 1934, Serial No. 717,766

2 Claims. (CL 189—37)

The present invention relates to metal structural elements, and more particularly to sheet metal beam or column structure particularly adapted to fabrication by spot welding, although the parts are well adapted to being secured by riveting or other suitable forms of attachment.

The invention has particular reference to light structural work, as light busses, light rail cars, air craft, marine super-structures and the like.

10 The main object of the invention is the provision of a girder, beam or column structure capable of giving maximum strength for the weight of material employed, with simplicity and ease of construction, of a form capable of fabrication by machine spot welding especially on an automatic machine of the type known as a "progressive welder", and amenable to use as a structural element in the fabrication of structures by spot welding, and in a manner which makes possible the economical use of relatively expensive high tensile material, such as stainless steel.

An ancillary object is the provision of a beam or column having the above qualities and composed of elements capable of being formed from high tensile sheet material with substantially no spring-back and with a definite permanent set, that is one in which most of the deformation is in the plastic range rather than in the elastic range, and this by a simple rolling process of the nature of what might be termed brake rolling in which the metal is simply bent, and considerable tolerance is permitted in accuracy of adjustment of rollers, as distinguished from die rolling in which there is a substantial flow of metal and the adjustment of the rollers with respect to the gauge of the metal must be made with extreme exactitude.

The above and other objects and advantages of the invention are attained by the novel construction arrangement and cooperative relation of parts as will be clearly set forth in the following specification, reference being had to the drawing accompanying the same.

In the drawing:

45 Fig. 1 is a perspective view of one of the elements used in the construction of the improved beam.

Fig. 2 is a perspective view of a completed beam.

50 Fig. 3 is a transverse section through the completed beam of Fig. 2 on an enlarged scale.

Fig. 4 is a transverse section of a modification particularly adapted to beams of relatively small section.

55 Fig. 5 shows attachment of narrow gusset.

Fig. 6 shows attachment of wide gusset.

Referring to the drawing in detail, and first to Figures 1 to 3, the beam as here shown is composed of four wall elements, a pair of spaced opposed top and bottom wall elements 1 and 2, 5 and a pair of spaced opposed side wall elements 3 and 4. These wall elements are substantially identical in shape and dimensions. Each element is of the form shown in Fig. 1, which is that of a trough member having a central longitudinal bead 5 in the bottom wall of the trough projecting inwardly of the trough, to approximately the depth of the trough. It will be noted that this particular form of section is capable of being simply bent into form from strip sheet material, which bending may be accomplished through the use of any suitable or other known form of bending means such as bending rollers, and that because of the flat surfaces and relatively abrupt or sharp angular changes in contour it is capable of being bent into the shape shown with a definite permanent set and with substantially no spring-back, which latter is prevented by the avoidance of curved contours or rounded corners. This shaping of the beam with flat surfaces and definite breaks in contour makes possible a definite permanent set in the deformation without the use of close fitting dies, and with substantially no change in gauge due to the deformation, which quality renders it capable of economical production from strip stainless steel without detriment to the valuable characteristic qualities of this material, and makes for economy in quantity production due to its simplicity and economical use of material, and the simplicity of apparatus necessary for its formation.

The beam construction shown in Figures 2 and 3 consists of four elements such as shown in Fig. 1, which may be exactly alike, or may vary slightly in dimensions according to the desired cross sectional dimensions of the finished beam or column. In this form it comprises the pair of opposed wall members 1—2, facing inwardly of the beam, with a pair of opposed side wall members 3—4, positioned within and between the first two members and facing outwardly of the beam. The sides 6 of the channel elements 3 and 4 are seated against the inner surfaces of the bottom wall of the channel members 1 and 2 between the base edges of the beads 5, and the side walls 6 of the members 1 and 2. The side walls 6 of the channel members 3 and 4 are preferably, substantially the width of the spaces between the base of the bead and the side wall of the upper 55

and lower members 1 and 2. The parts are secured together in the relation shown, to form a rigid beam structure by spot welding the flanges 6 of the side elements 3-4, to the bottom walls 5 of the top and bottom members 1 and 2 where such flanges and bottom walls lie in flat contact with each other, which welding may be done by a straight line of spot welds, as shown in Fig. 2 where the spot welds are indicated by the number 7.

An advantage of having the width of the flanges 6 of the side wall members substantially fill the spaces between the beads 5 and the side wall 6 of the upper and lower members, is that it not only enables the parts to be properly held in place for welding without the use of elaborate jigs but substantially eliminates the chance of making the welds at the edge of the side walls 6 of the side members in welding them to the top members. As the space around the portions to be welded together, that is, around the contacting surfaces of the sides 6 of the side channel members and the bottoms of the top and bottom members is clear and unobstructed in a longitudinal direction, the parts so assembled and related lend themselves readily to being welded by a "progressive welder" or automatic straight line spot welder.

As will be clear from Fig. 3, the sides 6 of the channel elements are of such depth that on the outside elements 1 and 2 they may function both as stiffening means and attaching flanges for effecting a spot welded connection between a finished beam and gussets or other structural elements. The finished beam or column is thus provided with a set of four L-section flanges formed by the side walls of the outside channel section elements 1 and 2, and a portion of their bottom walls between the side walls and the bases of the beads 5. There is one such L-section attaching flange on each corner edge of the beam, the four flanges being so directed as to enable the beam to be spot welded to a flat surface on any of these four sides by two parallel lines of spot welds. Where gussets or other flat structural members are to be secured to the top and bottom sides of the beam as positioned in Figures 2 and 3 by spot welding, overlapping of the second group of spot welds with the original spot welds used in forming the beam may be avoided either by omitting spot welds from those portions of the beam where such other structural elements are to be attached, or by the use of a beam completely welded and taking care that in the subsequent welding thereto of other structural elements the second line of welds are staggered in relation to the first.

Where attachment is to be made against the sides of the beam as shown in Figures 2 and 3, to gussets or other flat structural elements, the spot welds are made through the side walls 6 of the top and bottom channel sections. Reference to Fig. 3 will indicate how the application of one member of the spot welding tool to the inner surface of the L-shaped attaching flange is permitted by the shape and arrangement of the elements constituting the beams, in which figure two electrode members of the spot welding tool are indicated in dotted lines at 8 and 9. It will also be clear from Fig. 3 how the particular form of bead 5 affords maximum strength and at the same time permits ready access of the inner electrode of the welding tool. Fig. 3 also shows in dotted lines the position of a pair of electrodes

10 and 11 for welding gussets or the like to the horizontal portions of the L-shaped flanges.

Where relative narrow gussets are to be attached, especially to the outer members of the L-section flanges, a suitable shaped welding electrode 13 may be inserted under the flange from the side of the gusset as indicated at Fig. 5, and where the gussets are of too great a width to allow for this, the gussets may be made of the double type or provided with intermediate open sections to permit the insertion of the welding tool 13 as indicated in Fig. 6.

Where the beam is to be made quite small, say of a depth of 2 inches or less, the modification of Fig. 4 is used, in which the elements are like those of the beam shown in Figs. 1 to 6, in all respects except that the side elements 14 and 15 are formed with the central longitudinal beads 16 projecting outwardly of the channels. As indicated in dotted lines in Fig. 4, this allows ready access to the inside of the L-shaped edge flanges of the smaller beam with the same set of electrodes 8 and 9 as used on the large beam.

A practical advantage of the invention embodied in the form shown in Fig. 2, is that all four elements constituting the beam are identical thus effecting economy in machinery for forming the elements.

A marked practical advantage of the peculiar section of the present beam, as will be observed from inspection of both Figs. 3 and 4, is that the beam may be slightly compressed in the direction of either its width or its depth, or both without substantial spring-back, to effect slight alteration in its cross dimensions where expediency requires, without weakening the beam, and without substantial change in the section contour.

While I have thus herein shown and described certain specific embodiments of my invention for the sake of disclosure, it is to be understood that the invention is not limited thereto, but contemplates all such modifications and variations thereof as fall fairly within the scope of the appended claims.

What I claim is:

1. A box section beam comprising top and bottom members of inwardly facing channel section, and side members of outwardly facing channel section having their side walls secured to the bottom walls of the top and bottom members, all of said members having a section of substantially the same shape and size, each of said channel sections having a flat sided V-shaped symmetrical beading projecting inwardly of the channel at an abrupt angle to the bottom wall and leaving flat bottom portions on each side of a width substantially equal to the height of the side walls, the side walls of the top and bottom members extending beyond the side walls of the side members whereby structural elements may be secured thereto.

2. A box section beam formed from high tensile sheet metal with a definite permanent set which comprises four substantially identical wall elements each of which has flat body portions and an intermediate V-shaped reinforcing channel between said flat body portions and flat flanged portions at substantially abrupt angles to said body portions exterior thereof, said wall elements being paired in opposed relation, the flat body portions of one pair of opposed elements acting as chord members reinforced by the intermediate V-shaped channel and the exterior flanged portions, the second pair of opposed ele-

ments acting as webs and reinforced by intermediate V-shaped channels and the exterior flanges, the flanges of the acting web elements being secured to the body portions of the acting chord elements, said acting chord elements constituting cover members to form a box beam with

the web members, the flanges of all elements being exposed to facilitate welding, such beams being relatively compressible in width and depth to effect slight alteration in its cross sectional area.

ALBERT G. DEAN.
